WINDOW SASH FASTENER

Filed Feb. 11, 1928

INVENTOR
Joseph Neiser,
BY *Mme Leo*.
ATTORNEY

UNITED STATES PATENT OFFICE.

JOSEPH NEISER, OF CHARLOTTE, NORTH CAROLINA.

WINDOW-SASH FASTENER.

Application filed February 11, 1928. Serial No. 253,667.

My invention relates to window sash fasteners and an object thereof is to provide a window sash fastener whereby the cooperating sashes of a window may be fastened in various adjusted positions.

Further the invention provides a sash fastener embodying a pair of sash engaging elements which are detachably and longitudinally adjustably connected together so that 10 the sashes may be readily raised or lowered or fastened in predetermined positions.

With the preceding and other objects and advantages in mind, the invention consists in the novel combination of elements, constructions and arrangement of parts to be hereinafter specifically referred to, claimed and illustrated in the accompanying drawings, wherein:

Figure 1 is a front elevation of a window 20 having my invention associated therewith;

Figure 2 is an enlarged vertical sectional view of the same taken on line 2—2 of Figure 1;

Figure 3 is a transverse section taken on 25 line 3—3 of Figure 2;

Figure 4 is a perspective of the bracket embodied in the invention;

Figure 5 is a perspective of one of the elements embodied in the invention; and

Figure 6 is an elevation of the blank used in forming the bracket disclosed in Figure 4;

Figure 7 is a modified embodiment of the invention.

Referring to the invention in detail an angle bracket 5, having a vertically extending leg 6 and a horizontal attaching leg 7 to be secured upon the upper face of the lower sash of a window, is provided. The leg 7 is provided with a plurality of openings 8 for the reception of fastenings 9 which engage the sash.

At its upper end the leg 6 is formed with a pair of oppositely extending horizontally disposed lateral extensions 9' which are reversely bent against the upper end of the leg 6. At a point intermediate their ends the extensions are bent at right angles and lie against each other to provide an arm 10, the latter being disposed forwardly of the leg 6. Opposed transversely curved members 11 are formed on the free ends of the extensions 9' and define a vertically extending channel shaped member.

A threaded rod 12 adjustable longitudinal-

ly and removable from the channel shaped member is provided for engaging the upper sash of the window. A right angular extension 13 is formed on the upper end of the rod and terminates in an upwardly curved hook element 14 which is engageable in a recess 15 in the adjacent face of the upper sash. A plate 16, having an opening 17 in registration with the recess 15, overlies the latter and is secured to the sash by removable fastenings 18.

For the purpose of holding the threaded rod in predetermined longitudinal adjusted positions within the channel shaped member and thereby fasten the window sash at predetermined positions, frusto conical nuts 19 are threadedly received on the rod 12 upon opposite sides of the channel shaped member and are adapted to be threaded against the ends of the latter.

As particularly illustrated in Figure 2, the opposite ends of the socket are bevelled, as at 20, in opposite directions, while the adjacent face of the adjacent nuts are provided with bevelled recesses 22 for the reception of 80 these bevelled ends 21.

In use the extension 13 on the rod 12 is inserted through the opening 18 in the plate 16 to engage the hook with the upper wall of the recess 15 and the rod then swung downwardly to lie within the channel shaped member. After the sashes are arranged in closed or partly open position, the nuts 19 are threaded against the channel shaped member to hold the threaded rod against 90 vertical displacement.

In Figure 6 I have disclosed a modification of the invention. In this instance the bracket 5 is cast with an upstanding right angularly disposed arm 7' at its upper end 95 terminating in a vertically extending semi-circular or channel shaped member 8' for the reception of the threaded rod 12.

What is claimed is:—

1. In a fastener for two relatively movable slidable members, a channel shaped member to be fixed to one of such members, a rod longitudinally adjustable in the channel shaped member and engageable with the other member, and elements carried by 100 the rod upon opposite sides of the channel shaped member and engageable with the ends thereof to retain the rod against longitudinal shifting.

2. In combination a pair of vertically 110

movable sashes, a channel shaped member fixed to one sash, a rod vertically adjustable in the member and having one end engaging the other sash, and coacting elements on the rod and engageable with the ends of the socket to lock the rod against vertical displacement.

3. In a device of the character described, a bracket for attachment to a window sash, 10 a rod receiving member carried thereby, a threaded rod longitudinally adjustable in the member and having one end engageable with a second sash, and opposed nuts threaded upon the rod and engageable with the member to lock the rod against vertical movement.

4. A fastener comprising a bracket, a channel shaped member carried thereby and disposed at right angles thereto, a threaded rod longitudinally adjustable in the channel shaped member and having a hook element upon one end thereof and engageable with a member to be fastened, and opposed nuts upon the rod and engageable with the ends of the channel shaped member to lock the rod against longitudinal movement.

5. In a device of the character described, a bracket formed with lateral extensions at one end which are bent against the upper end of the bracket and thence bent at right angles to lie against each other and terminate in transversely curved members which

together define a channel shaped member, a longitudinal element adjustable in the channel shaped member and engageable with a 35 movable member, and means cooperating with the longitudinal element and channel shaped member to hold the longitudinal element against longitudinal movement.

6. In a device of the character described, 40 a bracket, a channel shaped member carried thereby and having its ends tapered in opposite directions, a threaded rod longitudinally adjustable in the channel shaped member and having means for attachment to 45 an object to be fastened, nuts threaded upon the rod and opposed to the ends of the channel shaped member and having recesses in their inner faces to receive the tapered ends 50 of the channel shaped member.

7. In a fastener, a channel shaped member for attachment to a movable body, a threaded rod longitudinally adjustable in the channel shaped member having one end engageable with a second body, and opposed nuts arranged upon the rod and engageable with the ends of the channel shaped member to lock the rod against longitudinal movement.

Signed at Charlotte, in the county of 60 Mecklenburg and State of North Carolina, this 30th day of January A. D., 1928.

JOSEPH NEISER.
